ASH TRAY

William George Vasey, New Westminster,
British Columbia, Canada

Application April 10, 1945, Serial No. 587,566

7 Claims. (Cl. 131—233)

1

My invention relates to improvements in ash trays.

It is common practice for cigarette smokers when desiring to discontinue smoking a cigarette and put said cigarette down, to rub the lighted tip into an ash tray to prevent it from continued smouldering. This act usually results in the cigarette being so damaged adjacent the charred tip as to render it unsightly and unfit for further use and even then the smouldering tobacco is not always put out. It is with the object of preventing this waste that the present invention is devised.

Some of the objects of the invention are to cut off the smouldering tip of the cigarette and trap it within a covered ash tray so that any smoke resulting from the burned tip of the cigarette will be completely confined within the closed tray; to provide for cutting off said tip so cleanly as to render the remainder of the cigarette neat and ready for further use; to prevent the escape of smoke from the ash tray and to provide openings through which cigarette butts may be dropped into said ash tray.

Referring to the drawings:

Fig. 1 is a plan view of the invention, with parts broken away.

Fig. 2 is a horizontal sectional view looking up into the cover and is taken on the line 2—2 of Figure 3.

Fig. 3 is a sectional view taken on the lines 3—3 of Figures 1 and 2.

Fig. 4 is a side elevational view of the cigarette receiving sleeve and its closure.

Fig. 5 is an enlarged sectional view taken on line 5—5 of Fig. 2 but showing the ash receiver and cover in upright position.

Fig. 6 is a sectional view taken on line 6—6 of Fig. 1.

Fig. 7 is a similar view to Fig. 2, showing the cutting blade at the end of its cutting stroke.

In the drawings like characters of reference indicate corresponding parts in each figure.

The numeral 1 indicates generally an ash tray comprising a base or ash receiver 2 and a cover 3. The cover is provided with a pair of internal lugs 4 each having an open ended slot which is adapted to embrace a pin 5 extending inwardly from the wall of the base to secure the cover in place.

On the surface of the cover a cigarette sleeve 6 is formed which has a cap 7 having side plates 7A hinged on pins 8 provided near the surface of the cover and to the rear of the sleeve, so that the cap will fall by gravity into closed position, upon the top of the sleeve. On the front upper edge of the cap 7 is a U-shaped projection 10 into the base of which the side of a cigarette, shown in full lines in Figure 4, is pressed rearwardly to tilt the cap and allow the burning tip which is below the projection 10 to be aligned with the passage 11 of the sleeve, so that it may

2

be dropped therein, as shown in dotted lines in Fig. 4.

A wall 13 is formed partially around the cover to form a depression for ashes and segmental openings 14 are formed therein for cigarette butts to pass therethrough. Concentrically mounted on a pin 16 on the underside of the cover 3 is a plate 17 having segmental openings 18 therein, which are adapted to be brought into register with the openings 14 of the cover when the plate is rocked about its pivot in the direction of the arrow shown in Figure 2. The plate is provided with an operating knob 19 connected to the plate by a stem 20 which passes through a slot 21 in the cover 3.

A portion of the plate 17 is offset adjacent the base of the stem 20 as at 23 and is provided with a pair of hollow shallow projections 24 for the purpose of engaging the centre line openings 20 of a razor blade 25 and the forward edge of the offset portion is provided with small upturned lugs 26, one only shown, for the purpose of engaging the cutaway corners of said blade. In order that the blade 25 shall be firmly held upon the offset portion of the plate, it is engaged by a keeper 28 which is upwardly bent at opposite ends as at 29 and 30, which ends bear respectively upon the plate 17 and on the razor blade 25.

The keeper 28 is fitted with a freely rotating thumb nut 32 which threadedly engages a stud 33 carried by the plate 17. The keeper 28 is provided on opposite sides adjacent the end 30 with small lugs 31 which are adapted to enter the hollow projections 24 of the plate and so prevent any rotational movement of the keeper about its nut 32 and stud 33. Projecting from the end 30 of the keeper is a step 36, see Figures 2 and 3, which is adapted to remain, when the plate 17 is in normal position as shown, directly under the passage 11 of the cigarette sleeve 6 and forms a stop to receive the lighted end of a cigarette prior to the tip of said cigarette being cut off by the razor blade 25. A shallow stop 37 having a face 38 is provided at the end of the stroke of the blade and is so set that the cutting edge of the blade will engage the length of the face when it comes into contact with said stop, the purpose of the stop being to ensure that the paper surrounding the cigarette is entirely severed. The plate 17 is provided with a pin 40, a second pin 41 extends downwardly from the stop 37 and a spring 42 extends between said pins to return the plate to normal position after manual operation.

As a means of preventing smoke from burning embers from passing out through the slot 21 through which the stem 20 extends, a thin strip 44 or shutter is mounted on the stem and is adapted to slide along the slot as the stem is moved. A light leaf spring 45 is secured to the inner end of the stem which bears at its outer

end upon the strip to keep the slot closed. The tension of the spring 45 is obviously very slight so as not to impair the action of the spring 42 in returning the plate to normal position.

In operating the device, ashes and cigarette butts lying on the cover 3 may be dropped into the base 2 by moving the knob in the direction of the arrow to bring the openings 14 and 18 into register. When it is desired to cut the burning tip from a cigarette, the lighted end of the cigarette is dropped into the passage 11 as hereinbefore described and allowed to come to rest upon the step 36, then the knob is moved, bringing the razor blade with a slice cut against the cigarette, severing said cigarette above the lower extremity of the paper with the blade coming to rest against the stop face 38, thus preventing any ragged edge in the paper. The blade 25 being set to slice the cigarette instead of making a shear cut, causes the cut tip to roll along the stop face 38 as it is severed and to fall freely below the blade since the step 36 has moved from under said tip and by virtue of the blade being tilted due to the offsetting of the plate 17 as at 23 the cutting edge is kept substantially in contact with the underside of the cover 3, thus aiding in making the cut a clean one.

If it becomes necessary to change the razor blade, the cover 3 is removed from the base 2 and the thumb screw 32 is unscrewed from the stud 33. This allows the keeper 28 to be lifted from the plate, so that the dull blade may be removed and another substituted. The new blade on being dropped into place upon the projections 24 becomes properly located and on replacing the keeper with its lugs 31 in said projections and screwing the thumb nut back onto the stud 33, the blade is securely held in appropriate position so that when the cover is put back into position the device is again ready for use.

What I claim as my invention is:

1. An ash tray having an ash receiver and a cover, a vertical sleeve having a passage communicating with the ash receiver and adapted to receive the burning end of a cigarette, a knife carrying structure mounted under the cover, a knife, a keeper for securing the knife to said structure, said knife being adapted to sweep across the passage to sever the tip from the cigarette, and a step carried by the keeper to limit the movement of the cigarette through said passage.

2. An ash tray having an ash receiver and a cover, a passage communicating with the interior of the cover adapted to receive the burning end of a cigarette, said cover having a slot, a knife structure rotatable within the cover, a knife carried by the structure and adapted to sever the tip from a cigarette projecting through said passage, means extending to the exterior of the ash tray to manually rock the knife structure, said means extending through said slot and a shutter movable with the knife structure for covering the slot during the manual movement of said structure.

3. An ash tray having a cover provided with a cigarette sleeve, said sleeve having a passage communicating with the interior of the ash tray, a knife structure within the cover adapted to sweep across the inner end of the passage to sever the burning tip from a cigarette inserted into the passage, a cap normally covering the cigarette sleeve, said cap having a projection to facilitate its being opened by side pressure from

the cigarette when being aligned with the passage and being mounted to close by gravity as the cigarette is removed from said sleeve, and means for operating the knife structure.

4. An ash tray having an ash receiver and a cover, said cover having a vertical passage extending therethrough and being adapted to receive the burning end of a cigarette, a rotatable plate mounted within the cover, and means accessible from the exterior of the ash tray for rotating the plate, said plate having a portion for supporting a razor blade, means for locating the razor blade thereon, a keeper detachably connected to the plate, said keeper having one edge adapted to engage the blade and devices adapted to engage the blade, locating means to prevent relative movement between the keeper and the plate.

5. An ash tray having an ash receiver and a cover, said cover having a vertical passage extending therethrough, said passage being adapted to receive the burning end of a cigarette, a rotatable plate mounted within the cover, means accessible from the exterior of the ash tray for rotating the plate, said plate having a portion offset at an angle to the plane of the cover for locating a razor blade on said plate, a keeper detachably connected to the plate, said keeper having one edge adapted to engage the blade and having lugs adapted to project through the blade to prevent relative movement between the keeper and the plate.

6. An ash tray having an ash receiver and a cover, said cover having a vertical passage extending therethrough, said passage being adapted to receive the burning end of a cigarette, a rotatable plate mounted within the cover, means accessible from the exterior of the ash tray for rotating the plate, said plate having a portion offset at an angle to the plane of the cover, means for locating a razor blade on said plate, a keeper detachably connected to the plate, said keeper having one edge adapted to engage the blade and devices adapted to engage the blade, locating means to prevent relative movement between the keeper and the plate.

7. An ash tray having an ash receiver and a cover, said cover having a vertical passage extending therethrough, said cover being adapted to receive the burning end of a cigarette, a rotatable plate mounted within the cover and means accessible from the exterior of the ash tray for rotating the plate, said plate having a portion for supporting a razor blade, means for locating the razor blade thereon, a keeper detachably connected to the plate, said keeper having one edge adapted to engage the blade and lugs adapted to extend through the blade to prevent relative movement between the keeper and the plate.
